CLAIM

The ornamental design for a tower heater, as shown and described.

DESCRIPTION

FIG. 1 is a front perspective view of a tower heater showing my new design;

FIG. 2 is a front elevational view of the tower heater shown in FIG. 1;

FIG. 3 is a rear elevational view of the tower heater shown in FIG. 1;

FIG. 4 is a left-side elevational view of the tower heater shown in FIG. 1;

FIG. 5 is a right-side elevational view of the tower heater shown in FIG. 1;

FIG. 6 is a top plan view of the tower heater shown FIG. 1; and,

FIG. 7 is a bottom plan view of the tower heater shown in FIG. 1.

The broken lines immediately adjacent the shaded areas represent the bounds of the claimed design while all other broken lines are directed to environment and are for illustrative purposes only; the broken lines form no part of the claimed design.

1 Claim, 6 Drawing Sheets
